The ornamental design for a splatter ball gun, as shown and described.

DESCRIPTION

FIG. 1 is a first perspective view of a splatter ball gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the splatter ball gun thereof;

FIG. 10 is an enlarged view of the selected portion 10 in FIG. 1;

FIG. 11 is an enlarged view of the selected portion 11 in FIG. 1;

FIG. 12 is an enlarged view of the selected portion 12 in FIG. 2; and,

FIG. 13 is an enlarged view of the selected portion 13 in FIG. 2.

The broken lines shown in the drawings depict portions of the splatter ball gun that form no part of the claimed design.
